UNITED STATES PATENT OFFICE

KNUT LARSSON, OF STOCKHOLM, SWEDEN, ASSIGNOR TO TELEFONAKTIEBOLAGET L. M.
ERICSSON, OF STOCKHOLM, SWEDEN, A COMPANY OF SWEDEN

TELEPHONE SYSTEM

Application filed February 25, 1930, Serial No. 431,278, and in Sweden February 28, 1929.

The invention relates to such telephone plants where the calls are received or registered in special call receivers available for a group of subscribers in common and to which 5 the subscribers' lines are automatically connected upon calls. More especially, the invention refers to such automatic or semi-automatic telephone plants where the call receivers are constituted by registers in which the 10 wanted subscriber's number is registered and which serve to control the setting of the selectors. In such systems the call receivers have hitherto been adapted to be connected by means of so called register finders or cord 15 finders to each of the junction lines or cord lines available for a group of subscribers' lines in common. The researches upon which the present invention is based have shown that the number of connection possibilities in such 20 register finders or cord finders is unnecessarily great in comparison with the requirements determined for a certain traffic frequency through the calculus of probabilities. The present invention has for its object to 25 utilize the results of said research in order to simplify and cheapen the switching arrangements required for the connection of the call receivers to the junction lines. The invention is substantially characterized in 30 that the call receivers appertaining to a group of calling lines are distributed among the junction lines belonging to the same line group in such a manner that each call receiver may be associated only with a limited 35 number of said junction lines.

The invention is not restricted to systems having registers but may be applied also in other systems having call receivers, by way of example such manual or semi-automatic 40 systems in which the wanted number is registered and made visible for the operator on a call indicator or the like.

The invention will be more closely described with reference to the accompanying 45 drawings. Figure 1 shows diagrammatically a known arrangement adapted to connect call receivers to junction lines, whereas Figures 2 to 5 show different embodiments according 50 to the invention. Figure 6 shows a circuit

diagram for an embodiment according to Figure 4.

In Figure 1, G_1 designates a group of junction lines or cord lines F which are available for a group of subscribers' lines in common. In the shown example each such junction line is provided with a call finder S through which the junction line may be connected to any one of the subscribers' lines belonging to the same subscriber's group and also to a selector V which may be a group selector or a final selector and through which the talking connection may be extended in known manner. To the same subscriber's group, a number of call receivers R , such as registers, are allotted which registers are available for all subscribers' lines in common in the group as each call receiver over an appertaining line E may be connected to any one of said junction lines F . The possibilities of connection are indicated on the drawings by means of small circles in the points of intersection between the lines E and F . In the shown example it is assumed that the subscriber's group comprises five hundred subscribers' lines, thirty two junction lines F and seven call finders R . The connection of a call receiver to a junction line may take place by means of switching apparatus of arbitrary kind, such as register finders allotted to the different junction lines, or cord finders allotted to the different call receivers.

Figure 2 shows an arrangement according to the invention for the same subscriber's group having the same number of junction lines and call receivers. According to this embodiment the junction lines are divided in a number of sub-groups each allotted to their special call receiver. Each call receiver has thus no longer any possibility, as in Figure 1, to be connected to all the junction lines in the group but the junction lines are distributed among the different call receivers in such a manner that each call receiver may be connected only to a limited number of junction lines. The call receiver R_1 has thus access only to the five first junction lines, the call receiver R_2 only to the five following junction lines, etc. the system being pref-

erably arranged in such a way that the different call receivers are allotted to an equal or nearly equal number of junction lines. Due to the fact that the different call receivers are uniformly distributed among the junction lines and that each calling subscriber's line has the possibility to connect itself to any one of the junction lines, an arrangement according to Figure 2 is nearly 10 equivalent to an arrangement according to Figure 1 as regards its capability to receive and to take care of the traffic at the same traffic frequency. The switching arrangements through which the call receivers are 15 connected to the junction lines may be of arbitrary kind. They may, by way of example, consist of call finders allotted to the different call receivers the arrangement according to Figure 2 then offering the advantage 20 over the arrangement according to Figure 1 that the call finders have a considerably less capacity and consequently may be made smaller and cheaper.

To obtain a distribution as uniform as possible of the calls among the different junction lines or the call receivers respectively the system is preferably arranged in such a way that each call in known manner causes the starting of a plurality of call finders S. 25 Then call distributors or starting distributors of known kind may be advantageously used which are started upon calls and, in different setting positions, successively start a number of call finders until a suitable number thereof have been started. The starting 30 of said call finders is then controlled by the call distributor in such a manner that the latter in different setting positions starts call finders appertaining to different call receivers 35 and, preferably in each setting position, starts a number of call finders appertaining to separate call receivers. In the arrangement according to Figure 2, the call distributor, by way of example, in one position 40 starts two call finders appertaining to the call receiver R_1 and in next position two call finders appertaining to the call receiver R_2 etc. The switching then proceeds in known manner so that the call finder first 45 finding a calling line is engaged for the connection, other call finders then stopping. The appertaining call receiver may thereupon by means of its cord finder be connected to the junction line in question.

50 The switching time for connecting a subscriber's line to a call receiver may be reduced if the switching arrangement instead is carried out in such a manner that a free call receiver in advance is connected to one 55 of the appertaining junction lines being free at that time. Then only the call finder appertaining to said junction line will be started at the call whereas other junction lines and finders appertaining to the same call receiver which are not previously engaged, are

marked as engaged. The call receiver is then adapted to connect itself automatically to another junction line as soon as a connection has been completed. In an arrangement according to the invention the subscriber's line will consequently be connected to the call receiver in the same moment as the appertaining call finder is connected to a subscriber's line. 70

An important advantage of the invention 75 resides therein that it offers a possibility to make use of simple electromagnetic relays for connecting the call receivers to the junction lines. This is of course also possible in the known arrangement according to Figure 1 but in the latter such an arrangement should become very uneconomical dependent upon the great number of relays then required. In an arrangement according to Figure 1 the number of relays required per junction line is thus equal to the number of call receivers whereas the arrangement according to Figure 2 only requires one relay per junction line. The invention renders thus possible the complete elimination of the 80 call finders or register finders hitherto used. In practice, this does not, however, involve that said finders must be substituted by relays because already in known systems having finders each junction line is provided 85 with a relay to bring about the final connection with the call receiver. As said relays already provided for may be immediately utilized for connecting up the call receivers in an arrangement according to the invention, said invention involves thus an immediate saving of said finders. At the same time the advantage of a momentary connection of the call receiver to the junction line is gained. 90

Figure 3 shows an embodiment of the invention in which a number of call receivers is common to two groups of junction lines G_1 , G_2 corresponding to two subscribers' groups each comprising five hundred subscribers. Each group G_1 , G_2 comprises as before thirty-two junction lines F. It is assumed that a number of sixteen call receivers is adequate for the combined traffic in said two groups. The system is then arranged in such a manner that each call receiver may connect itself to a number of junction lines in both groups the different call receivers being distributed among the different junction lines in each special group 95 in similar manner as in Figure 2. Then only two junction lines in each group will, however, be allotted to each call receiver. Otherwise the connection of the call receivers to the junction lines and the connection of the junction lines to the subscribers' lines may take place in similar manner as described in connection with Figure 2.

Figure 4 shows an embodiment where thirty five call receivers are common to five

groups G_1 to G_5 of junction lines which groups each corresponds to five hundred subscribers' lines each group G_1 to G_5 preferably comprising thirty five junction lines 5 i. e. the same number as the number of call receivers. Each call receiver may then be connected to only one junction line in each group in the manner shown on the drawings.

Figure 5 shows finally a modification of 10 the arrangement according to Figure 4 according to which modification each call receiver has a possibility to connect itself to two junction lines in each group, whereas at the same time each junction line is adapted 15 to obtain connection to two different registers in the manner illustrated by the circles in the points of intersection between the different lines. Through the increased connection possibilities thereby offered the number 20 of call receivers and the number of junction lines in each group may be reduced in relation to the arrangement according to Figure 4. In Figure 5 there are thus thirty two call receivers common to all the subscribers' 25 groups and each group comprises only thirty two junction lines.

Figure 6 shows an application of the invention in automatic telephone system having registers and power driven selectors 30 which latter are of that kind the contact arm of which has a turning motion and a radial motion in the same plane. The arrangement will be explained in other parts by the following description of the switching operation.

Upon calls the line relay LR is actuated in ordinary manner a circuit being then closed through a group relay LGR common to a group of subscribers over the contact 1 of 40 LR. The relay LGR closes in turn a test circuit through a starting relay SSR₂ over the contact 2 of LGR. The relay SSR₂ is common to all the subscribers' lines in the five hundred group in question. When said relay is energized it closes a number of circuits 45 3 for a number of call finders S free for the time being. Said circuits extend over contacts of a call distributor SS which is started by the energization of its clutch magnet over 50 a circuit 4. In the first moment only circuits 3 are closed for that number of call finders S which are connected to the contacts in the position taken up by the call distributor for the time being. The circuit 3 extends in 55 the normal position of the sequence switch SOS of the call finder over a contact thereof whereby is ascertained that the sequence switch takes up its normal position. Said circuit further extends over a contact not 60 shown in the group selector which is closed only in the eventuality of the group selector taking up its normal position. In the circuit 3 a relay RS₈ is included which now closes a circuit 6 including a relay RS₅ which in turn 65 closes a circuit 7 through the rotary magnet

CVS of the finder said finder being then started to search that contact row in which the calling line is connected up. The relay RS₅ then shifts the circuit 3 so that the relay RS₈ instead is energized over a current path 70 8 including a cut off relay SSR₄. The latter relay is so adjusted that it is actuated first when a certain number of relays RS₈ are connected in parallel to the circuit 8. By this arrangement the number of started finders is limited as the relay SSR₄ upon being energized interrupts a circuit 4 and thereby 75 brings the call distributor to stop. When the finder finds the contact row in question a current path 9 including a test relay RS₁ is closed which relay locks itself over its contact 10 and closes a current path 11 including a relay RS₄ having a low resistance. Hereby the relay RS₅ is shunted so that it is de- 80 energized.

The starting relays RS₅ for all call finders appertaining to the same register REG are connected in parallel to the portion of the circuit 6 extending from the register. Through the connection of the relay RS₄ into circuit in parallel with said portion of the circuit 6 the other call finders are marked as engaged as the appertaining relay RS₅ then is unable to attract its armature. When the relay RS₁ was energized the circuit 7 was interrupted and the turning motion of the finder stopped. At the same time the sequence switch SOS was energized over a current path 12 whereby it was brought to its third position. In said position a circuit 13 is now closed through the magnet CRS whereby the finder is started in radial direction. When the finder finds the calling subscriber's line a new circuit 14 is closed for the test relay RS₁ which is then energized and interrupts the circuit 13 whereby the selector is brought to stop. At the same time the clutch magnet of the sequence switch is energized over a current path 15 whereby the sequence switch is brought to its fourth position. In said position a circuit 16 is closed for that relay RS₅ which connects the register REG to the junction line in question. As soon as the register has been connected into circuit a buzzer signal is sent in known manner to the calling subscriber which thereupon sends current impulses in known manner which actuate the relay RR₄ in the register whereby the register is set according to the wanted number. When the register has been set, the group selector is started thereby that a circuit is closed over the line branch La. The setting of the selector thereupon takes place in known manner by sending back impulses over the line branch Lb which impulses actuate a relay 120 RR₇ in the register. After the call connection has been completed a circuit 17 is closed whereby the sequence switch is brought to the sixth position which is the speaking 125 position. At the same time the register is 130

disconnected which thereupon may be engaged to establish connections over other junction lines appertaining thereto. As long as the register operates the appertaining junction lines which are not engaged by a talking connection are marked as engaged in that the contact 18 in the circuit 6 is open which contact is closed only when the register takes up its normal position.

10 I claim:

1. An arrangement in telephone plants provided with calling lines, junction lines and call receivers, said calling lines being automatically connected to the junction lines and 15 to the call receivers over the junction lines, such receivers comprising registers, operator's positions and similar instruments, the call receivers belonging to a group of calling lines being distributed among junction lines 20 appertaining to the same line group in such a manner that each call receiver may be connected only to a limited number of said junction lines.

2. An arrangement as described in claim 1, 25 relating to plants comprising a plurality of groups of calling lines, each allotted to one group of junction lines; in which the junction lines appertaining to the same call receiver are distributed among different line 30 groups in such a manner that the call receivers will be available for a plurality of groups of calling lines.

3. An arrangement as described in claim 1, 35 in which each junction line is adapted to be connected to only one call receiver whereas each call receiver may be connected to several of the junction lines belonging to the same line group.

4. An arrangement as described in claim 1, 40 in which each junction line is adapted to be connected to several of the call receivers belonging to the same line group.

5. An arrangement as claimed in claim 1, 45 relating to plants comprising a plurality of groups of calling lines, each allotted to one group of junction lines; in which the junction lines appertaining to the same call receiver are distributed among different line groups in such a manner that the call receivers will be 50 available for a plurality of groups of calling lines; and in which the number of call receivers common to a plurality of line groups is substantially equal to the number of junction lines in each individual group.

6. An arrangement as claimed in claim 1, 55 relating to plants comprising a plurality of groups of calling lines, each allotted to one group of junction lines; in which the junction lines appertaining to the same call receiver are distributed among different line groups in such a manner that the call receivers will be 60 available for a plurality of groups of calling lines; and in which the number of call receivers common to a plurality of line groups is substantially equal to the number of junc-

tion lines in each individual group, and in which when a call receiver is engaged by a junction line the other junction lines belonging to the same call receiver are adapted to be marked engaged and thereupon remain 70 marked in said manner until the call receiver is again free.

7. An arrangement as claimed in claim 1, 75 relating to plants comprising a plurality of groups of calling lines each allotted to one group of junction lines; in which the junction lines appertaining to the same call receiver are distributed among different line groups in such a manner that the call receivers will be 80 available for a plurality of groups of calling lines; and in which the number of call receivers common to a plurality of line groups is substantially equal to the number of junction lines in each individual group; and in which a call causes the starting of a plurality 85 of call finders, and only such call finders are adapted to be started over which communication may be established with registers which are free for the time being.

8. An arrangement as claimed in claim 1, 90 relating to plants comprising a plurality of groups of calling lines, each allotted to one group of junction lines; in which the junction lines appertaining to the same call receiver are distributed among different line groups 95 in such a manner that the call receivers will be available for a plurality of groups of calling lines; and in which the number of call receivers common to a plurality of line groups is substantially equal to the number of junction lines in each individual group; and in which a call causes the starting of a plurality 100 of call finders, and only such call finders are adapted to be started over which communication may be established with registers which are free for the time being; in which those call finders which are simultaneously 105 started belong to different registers.

9. An arrangement as claimed in claim 1, 110 relating to plants comprising a plurality of groups of calling lines, each allotted to one group of junction lines; in which the junction lines appertaining to the same call receiver are distributed among different line groups in such a manner that the call receivers will be 115 available for a plurality of groups of calling lines; and in which the number of call receivers common to a plurality of line groups is substantially equal to the number of junction lines in each individual group; and in which a call causes the starting of a plurality 120 of call finders, and only such call finders are adapted to be started over which communication may be established with registers which are free for the time being; the call finders being adapted to be started successively by means of a starting distributor which in different setting positions starts 125 call finders belonging to different registers.

10. An arrangement as claimed in claim 1, 130

- relating to plants comprising a plurality of groups of calling lines each allotted to one group of junction lines; in which the junction lines appertaining to the same call receiver are distributed among different line groups in such a manner that the call receivers will be available for a plurality of groups of calling lines; and in which the number of call receivers common to a plurality of line groups is substantially equal to the number of junction lines in each individual group; and in which a call causes the starting of a plurality of call finders, and only such call finders are adapted to be started over which communication may be established with registers which are free for the time being; the call finders being adapted to be started successively by means of a starting distributor which in different setting positions starts call finders belonging to different registers; the starting distributor in each setting position being adapted to start call finders belonging to different registers.
11. An arrangement as claimed in claim 1, relating to plants comprising a plurality of groups of calling lines, each allotted to one group of junction lines; in which the junction lines appertaining to the same call receiver are distributed among different line groups in such a manner that the call receivers will be available for a plurality of groups of calling lines, and in which the number of call receivers common to a plurality of line groups is substantially equal to the number of junction lines in each individual group, and in which a call causes the starting of a plurality of call finders, and only such call finders are adapted to be started over which communication may be established with registers which are free for the time being, in which those call finders which are simultaneously started belong to different registers, and in which only one of the call finders appertaining to each individual register is started when a call is made.
12. An arrangement as claimed in claim 1, relating to plants comprising a plurality of groups of calling lines, each allotted to one group of junction lines; in which the junction lines appertaining to the same call receiver are distributed among different line groups in such a manner that the call receivers will be available for a plurality of groups of calling lines, and in which the number of call receivers common to a plurality of line groups is substantially equal to the number of junction lines in each individual group; and in which a call causes the starting of a plurality of call finders, and only such call finders are adapted to be started which are free for the time being; in which those call finders which are simultaneously started belong to different registers; and the register immediately after completed connection automatically connects itself to one of the appertaining junction lines free for the time being.
13. An arrangement as claimed in claim 1, relating to plants comprising a plurality of groups of calling lines, each allotted to one group of junction lines, in which the junction lines appertaining to the same call receiver are distributed among different line groups in such a manner that the call receivers will be available for a plurality of groups of calling lines; and in which the number of call receivers common to a plurality of line groups is substantially equal to the number of junction lines in each individual group, and in which a call causes the starting of a plurality of call finders, and only such call finders are adapted to be started which are free for the time being, in which those call finders which are simultaneously started belong to different registers, and the register immediately after completed connection automatically connects itself to one of the appertaining junction lines free for the time being, each register being provided with a finder for connecting the register to one of the appertaining junction lines.
14. An arrangement as claimed in claim 1, relating to plants comprising a plurality of groups of calling lines, each allotted to one group of junction lines; in which the junction lines appertaining to the same call receiver are distributed among different line groups in such a manner that the call receivers will be available for a plurality of groups of calling lines; and in which the number of call receivers common to a plurality of line groups is substantially equal to the number of junction lines in each individual group; and in which a call causes the starting of a plurality of call finders, and only such call finders are adapted to be started over which communication may be established with registers which are free for the time being; in which those call finders which are simultaneously started belong to different registers; and in which only one of the call finders appertaining to each individual register is started when a call is made, the registers being adapted to be connected to the junction lines by means of momentarily operating switching members.
15. In a telephone exchange system a main group of calling lines, a number of junction lines accessible in common to all lines of said main group and divided into a number of sub-groups, automatic switches adapted to connect a calling line with a junction line in any one of said sub-groups, a number of call registering devices individually allotted to different sub-groups of junction lines, and means for automatically connecting said call registering devices with any one of the appertaining junction lines.
16. In a telephone exchange system a plurality of main groups of calling lines, a cor-

- responding number of main groups of junction lines the junction lines of each group being accessible in common to the corresponding group of calling lines and divided 5 into a number of sub-groups, automatic switches adapted to connect a calling line with any one of the appertaining junction lines, a number of call registering devices accessible in common to a plurality of main 10 groups of calling lines and individually allotted to different sub-groups of calling lines in each main group of such lines, and means for automatically connecting said call registering devices with a calling line.
- 15 17. A telephone system as claimed in claim 16, in which the call registering devices accessible in common to a plurality of main groups of calling lines are provided in a number equal to the number of junction lines 20 in each main group.
18. In a telephone exchange system a main group of calling lines, a number of junction lines accessible in common to all lines of said main group and divided into a number of 25 sub-groups, automatic switches adapted to connect a calling line with a junction line in any one of said sub-groups, a number of call registering devices each of which is individually allotted to a different sub-group of 30 junction lines, and relays for connecting each of said call registering devices in the appertaining junction lines.
19. In a telephone exchange system a main group of calling lines, a number of junction 35 lines accessible in common to all lines of said main group and divided into a number of sub-groups, call finders associated with said junction lines and adapted to connect a calling line with a junction line in any one of 40 said sub-groups, a number of call registering devices individually allotted to different sub-groups of junction lines, means for automatically connecting said call registering devices with any one of the appertaining junction 45 lines, and means comprising a starting distributor for automatically starting a number of call finders in succession, said starting distributor being adapted in different setting positions to start call finders associated 50 with different sub-groups of junction lines.
20. A telephone system as claimed in claim 19, in which the starting distributor is adapted in each setting position to start a plurality of call finders associated with different 55 sub-groups of junction lines.
21. A telephone system as claimed in claim 19, in which the starting distributor is adapted to start only one call finder of each sub-group of junction lines.
- 60 In testimony whereof I affix my signature.
KNUT LARSSON.
